(57) CLAIM

The ornamental design for transparent storage box for nail polish, as shown and described.

DESCRIPTION

FIG. 1 is a perspective view thereof, showing my new design in a folded position;

FIG. 2 is another perspective view thereof, showing my new design in a unfolded position;

FIG. 3 is a front plan view thereof;

FIG. 4 is a back plan view thereof;

FIG. 5 is a left plan view thereof;

FIG. 6 is a right plan view thereof;

FIG. 7 is a top plan view thereof; and,

FIG. 8 is a bottom plan view thereof.
